Primary Examiner — Catherine R Oliver-Garcia

(74) Attorney, Agent, or Firm — Michael J. Feigin, Esq.;
Feigin and Fridman LLC(57) **CLAIM**

The ornamental design for an animal trap, as shown.

DESCRIPTION

FIG. 1 is a top and side perspective view of the animal trap;
 FIG. 2 is a top and opposite side perspective view thereof;
 FIG. 3 is a front elevation view thereof;
 FIG. 4 is a rear elevation view thereof;
 FIG. 5 is a right side elevation view thereof;
 FIG. 6 is a left side elevation view thereof;
 FIG. 7 is a top plan view thereof;
 FIG. 8 is a bottom plan view thereof; and,
 FIG. 9 is a top and side perspective thereof, shown in a
 different position.

The broken line showing of portions of the animal trap is
 included for the purpose of illustrating only and forms no
 part of the claimed design.

1 Claim, 9 Drawing Sheets(56)
